O. V. Thiel
ATTORNEY

UNITED STATES PATENT OFFICE

WILBUR H. ARMACOST, OF NEW YORK, N. Y., ASSIGNOR TO THE SUPERHEATER COMPANY, OF NEW YORK, N. Y.

HEAT EXCHANGER OR DESUPERHEATER

Application filed January 2, 1930. Serial No. 418,086.

The present invention relates to the art of heat exchange and aims to provide heat exchangers which are economical to manufacture and have a high capacity per unit volume.

In many installations of heat exchangers and substantially all those used for desuperheating steam, it is preferred to employ exchangers of the indirect type transferring the heat through the walls of tubes or the like. In such installations, it has been found that the rate of heat transfer per unit area of surface is very great, so that when liquid is used for absorbing the heat from the heating fluid, large quantities of vapor bubbles rise from the heat transferring surface in contact with the lower portion of the liquid and often the quantity of vapor thus developed is so large that the top surface of the liquid is insufficient to permit the vapor to disengage itself from the liquid without causing foaming or carrying along liquid particles with the vapor. A second difficulty which has been experienced in this type of apparatus is that the bubbles rising from the lower portion of the heat transferring surface rise into contact with the upper portions of such surface and, when the apparatus is working at high capacity, thereby insulate the upper portion of heat transferring surface to such an extent that it becomes almost useless. A third difficulty encountered in the indirect tubular type of heat exchanger has been to regulate its capacity for heat transferring or desuperheating. Ordinarily this has been done by changing the liquid level in the apparatus, but, in the ordinary type of device, a small change of liquid level has resulted in such a large change in capacity or the amount of desuperheating that the operatives have not been able in practice to adjust the apparatus satisfactorily to meet changing conditions.

It is the object of the present invention to provide a heat exchanger adapted for use as a superheater and which will avoid the above mentioned difficulties.

In accordance with my invention, the area of the liquid containing chamber taken up by the tubes for the heating fluid is decreased at the upper levels of the device as compared

with the lower levels so that the surface at which vapor may disengage itself from the liquid is increased with increasing depth of the liquid.

Novel features of my apparatus are pointed out in the appended claims. My invention, however, will best be understood from a detailed description of a specific heat exchanger embodying the invention, and such a description will now be given in connection with the accompanying drawings in which

Fig. 1 is an elevational view partly in vertical section of a desuperheater in accordance with my invention.

Fig. 2 is a horizontal section on the line 2—2 of Fig. 1.

The apparatus illustrated in the drawings is a known type of desuperheater in which heating fluid such as steam to be desuperheated is supplied to the inlet chamber 8 of the steam chest 9 through the pipe 10 and passes from 8 into the outlet chamber 12 of the steam chest through a tube bundle designated generally by T and composed of inverted U-tubes. The tubes of bundle T extend upwardly and axially into a chamber 14 having a vertical axis and in which the transfer of heat occurs. The chambers 8 and 12 are closed at the top by a horizontal flue sheet 16 in which the open lower ends of the tubes of bundle T are fixed and above which the chamber 14 contains heat absorbing liquid, water being the liquid employed when the apparatus is used for desuperheating steam. Vapor produced in the upper chamber 14 may pass out through pipe 20 and, when saturated steam is produced in the chamber, pipe 20 is ordinarily connected back into pipe 10 so that the two bodies of steam may be thoroughly mixed in passing through the heat exchanger. The capacity of such an apparatus is usually varied by varying the liquid level in chamber 14 thereby varying the heat transferring surface in contact with the liquid.

In accordance with the invention, the top surface of the liquid is increased with increase of heat transferring surface in operation so as to avoid the difficulty above mentioned. For this purpose, the tubes in chamber 14 are shown as arranged in groups 26,

26a, 26b and 26c, the lengths of the tubes in the groups increasing from 26 to 26c. The vertical or axial legs of the U-tubes in the bundle T may be set into the sheet 16 at equal distances between centers, as shown, but, in accordance with the invention, the bridge portions of the tubes in adjacent groups are vertically spaced apart a materially greater distance than the space between the leg portions of the tubes in such groups. Thus it will be seen that the tubes in group 26 maintain a substantially even spacing throughout their entire lengths and the same is true of the tubes in groups 26a, 26b and 26c, and also the distance between the legs of the U's of tubes in adjacent groups such as 26 and 26a is substantially the same as that between the legs of tubes in group 26 or in group 26a, but the vertical distance between the bridge portions of tubes in adjacent groups, such as group 26 and group 26a, is much greater than the horizontal distance between the legs of such tubes. Consequently, if the liquid level in chamber 22 is raised above the upper ends 25 of the tubes of group 26, the free or top surface of the liquid available for disengaging the vapor is increased and the vapor bubbles rising along the vertical lengths of the tubes may spread toward the free space thus provided in the center of the tube bundle to thereby lessen the concentration of vapor along the upper portions of the vapor forming surfaces. Again when the liquid level passes the upper end of the tubes in group 30 26a an additional free top surface and free central space is provided and this also occurs when the liquid level is raised above the tubes in groups 26b and 26c respectively. Indicating the levels of the upper ends of groups 26, 35 26a, 26b and 26c respectively by horizontal lines B, C, D, and E and the bottom of chamber 14 by line A it has been found satisfactory in actual practice, to make the distances AB, BC, CD and DE respectively, proportional 40 to 24, 32, 48 and 96. With this specific arrangement of heat transferring elements, the apparatus has one-quarter of its full capacity with the liquid level at B, one-half its full capacity with the water level at C, three-quarters full capacity at D, and full capacity 45 at E.

A safety valve 22 is usually provided for chamber 14.

The operation of an apparatus in accordance with my invention will be in general obvious from the foregoing description.

For convenience of reference, however, it may be stated that as the heating fluid or steam to be desuperheated passes through tubes T, bubbles of vapor are formed which pass up along the vertical sections of the tubes, but as the stream of bubbles reaches the levels B, C, D and E at which the vertical spacing between the tubes is increased, the bubbles tend to spread toward the free

central space thus provided, thereby avoiding largely the tendency to foam and to insulate the upper heat transferring surfaces of the tubes. Furthermore, by spacing the tubes as described, the capacity of the apparatus changes relatively slowly between the levels B and C, C and D, and D and E respectively, so that the operator can adjust the capacity of the apparatus as desired without difficulty. 70 75

While two rows or layers of tubes have been shown in each group such as 26, it will be obvious that the separate groups may each comprise a greater or lesser number of layers. It will be obvious also that in order to increase the steam liberating surface in proportion to the increase in capacity with the depth of liquid, the number of tubes in each group should be quite small and the groups quite close together. However, the relative number and spacing of the tubes and groups as shown and described, has been found satisfactory in practice. 80 85

As the arrangement of tubes according to my invention involves using tubes having relatively large variations in length, the resistance to steam flow through the longer tubes may be relatively much larger than that through the shorter ones so that the steam flow in the groups of tubes is unequal. This may be avoided, if desired, by placing restrictions in the shorter tubes or by varying the sizes of the tubes in the different groups so that the longer tubes will have a greater internal diameter. 90 95 100

While I have disclosed a specific apparatus acting as a desuperheater and having U-tubes lying in vertical planes, it will be understood that the form of apparatus herein disclosed is illustrative only and that my invention may be applied to other types of indirect heat exchangers such, for instance, as one having straight horizontal tubes. 105

I claim:

1. A heat exchanger having a chamber for liquid, tubes for heating fluid passing through said chamber, said chamber and tubes being so proportioned and arranged that the area of the top surface of the liquid increases with increase in depth of the liquid, a pressure chamber connected to one end of each of said tubes, and another pressure chamber connected to the other end of each of said tubes. 110 115

2. A heat exchanger as set forth in claim 1 and in which the tubes are arranged in vertical planes. 120

3. A heat exchanger having a chamber for liquid having a vapor outlet, inverted U-tubes for heating fluid passing through said chamber, said tubes being arranged in groups and having the bridge portions of one group vertically above those of shorter groups and the bridge portions of the tubes in adjacent groups spaced vertically a greater distance 125 130

than the distance between the leg portions of said adjacent groups to provide a space for the vapor to diverge from the tube surfaces and to separate from the liquid surface, a pressure chamber connected to one end of each of said tubes, and another pressure chamber connected to the other end of each of said tubes.

4. A heat exchanger having a chamber and tubes therein for containing a heating fluid and a liquid therein in contact with the outsides of said tubes, said chamber and tubes having an arrangement such that the portion of the horizontal cross-section of the chamber outside said tubes increases in passing upward from the bottom of the chamber, a pressure chamber connected to one end of each of said tubes, and another pressure chamber connected to the other end of each of said tubes.

5. A heat exchanger comprising a chamber for liquid, U-tubes with legs extending longitudinally therein and for conducting a heating fluid therethrough, a liquid within said chamber in contact with said tubes, said chamber and tubes having an arrangement such that the portion of the horizontal cross-section of said chamber outside said tubes increases in passing upward from the bottom of the chamber, a pressure chamber connected to one end of each of said tubes, and another pressure chamber connected to the other end of each of said tubes.
